CLAIM

The ornamental design for a wheel or wheel cover, as shown and described.

DESCRIPTION

This application contains subject matter related to the following co-pending U.S. design patent application:

Application Ser. No. 29/528,496, filed May 29, 2015 and entitled “Wheel or Wheel Cover.”

FIG. 1 is a front view of a wheel or wheel cover showing our new design; and,

FIG. 2 is a perspective view thereof.

The broken lines in the drawing figures represent unclaimed environment only and form no part of the claimed design.
